UNITED STATES PATENT OFFICE.

CHARLES A. LIEB, OF NEW YORK, N. Y.

PNEUMATIC DISPATCH-TUBE.

SPECIFICATION forming part of Letters Patent No. 398,414, dated February 26, 1889.

Application filed November 23, 1888. Serial No. 291,643. (No model.)

To all whom it may concern:

Be it known that I, CHARLES A. LIEB, a citizen of the United States, and a resident of New York, in the county of New York and State of New York, have invented certain new and useful Improvements in Pneumatic Tubes, of which the following is a specification.

My invention relates to improvements in pneumatic tubes of the class illustrated and described in the United States Letters Patent granted to Henry Clay, dated November 4, 1884, and numbered 307,437, although not limited to pneumatic tubes of that specific construction.

More particularly described, my invention relates to certain valves which are employed in such lines of pneumatic tubing, both in the length of the tubing and also at the terminals, whereby the air-currents are compelled to continuously traverse the entire system of tubing, and through which the carriers may pass either for delivery at the terminals or to continue their desired course through the tubes; and the invention consists in substantially the construction and arrangement of the said devices hereinafter set forth and illustrated in the drawings hereof.

In all the figures of the drawings the same reference-letters indicate the same parts.

Figure 1 illustrates a sectional view of my invention when constructed and arranged to operate as a valve in the line of tubing. Fig. 2 illustrates a sectional view of my invention when constructed and arranged to operate as a valve-terminal. Fig. 3 illustrates a view, partly in plan and partly in section, of a short system of tubing with the receiving-cocks, line-valves, terminal-valves, and switch in position. It illustrates the operation of the several devices when in use. Fig. 4 illustrates an edge view, in elevation, of my valve. Fig. 5 illustrates a plan of the diaphragm-valve slideway and frame thereof. Fig. 6 illustrates an end view of the diaphragm-valve slideway and frame thereof.

Before describing the construction and operation of my invention it will be well to state that one of the advantages incident thereto is that it may be used either as a valve in the line of tubing for the purpose of de-

flecting the current of air, thus maintaining circulation without obstructing the passage of the carrier, or as a delivery-valve at the end of the main line, or at a sub-station 55 through which the carrier will pass and drop from the tube, the air-current continuing in circulation through the valve. All that is needful to effect this dual use of the invention is to change the location of the opening 60 in the side of the valve-case, as will be hereinafter set forth.

I will first describe the invention when arranged to act as a valve in this line of tubing and having special reference to Fig. 1. 65

A is a circular annular casing, preferably made of metal. B B are two side pieces adapted to be screwed to the edges of this annular casing A.

C is a diaphragm or partition which fits air-tight, or practically so, within the annular casing A. It may be cast in one piece with the annulus, as shown in Fig. 1, or it may be made separately and fitted in place and held therein in any suitable manner. 70

D D' are the ends of the line of pneumatic tube, which respectively enter and pass out of the lower part of the annular casing, as shown.

E is a gate, made, preferably, of thin sheet-steel. It slides in ways F F, which are fastened to the front of the diaphragm, as shown in Figs. 1, 2, 5, and 6. 80

G is a lever somewhat like a bell-crank lever, pivoted at H to lugs I, made on the annular casing, and J is a connecting-rod, which is pivoted to the bell-crank G and to lugs I', attached to the gates E, as shown—that is to say, there is a depression or recess, J², pressed into the back side of the gate, and the lugs are firmly riveted thereto, as shown. By this construction the rivet-heads do not interfere with the sliding of the gate, and it is easily made air-tight. The free end K of the bell-crank projects through a slot, K', in the end of the tube marked D, so that when the gate 90 is shut the free end of the bell-crank lies directly in the path of the carrier during its passage along the tube. 95

L L are slits or openings formed in both the ends D and D' of the pneumatic tube within 100 the casing and at opposite sides of the diaphragm C and gate E.

M is a spring-cushion or equivalent bunter, which receives the blow of the bell-crank lever when it is forced upward by the passage of a carrier, as will be hereinafter explained, 5 and as shown by dotted lines in Fig. 1.

N N' (see Fig. 4) are two holes drilled in the end of the plug N' of the spring-easing P, whereby it may be screwed in place.

Q is a branch pipe, which engages with an 10 opening, Q', on the side of the annular casing, through which the air-current passes, as will be hereinafter explained, whereby the continued circulation is maintained.

Referring now to Fig. 3, R is the outgoing 15 main-line tube, and S is the return main-line tube. T is the outgoing branch tube to substation U, and V is the return-tube, which joins the main-line return-tube, as shown. W is the tube which connects with the blower, 20 which generates the blast. A suction may be applied in any desired manner to the end of the return main-line tube, as at X, if desired.

Y Y' Y² are carrier receiving-cocks, substantially like those now in use in pneumatic 25 tube systems, and which do not require specific description here. Any preferred form thereof may be used.

ZZ' Z² are three of my new devices arranged as terminal valves—that is to say, in them 30 all the branch pipe for the continuation of the circulation of the air-blast enters the casing between the diaphragm and the inlet-pipe. Two of them, Z and Z', are located at the termini of two lines, or, in other words, at stations, and are provided with delivery-spouts A' A'. The other one, V², although in construction and operation the same as the terminal valves Z and Z', is not at the end of a line, but in the branch-line tube. Consequently, 40 instead of delivering the carrier out from the tube, it delivers it into the main-line return-tube, as hereinafter set forth.

Z³ is one of my devices arranged as a valve in the main line. Therefore in this construction the branch pipe Z⁴, for the continuation of the air-circulation, enters the casing A at that side of the diaphragm C which is farthest from the air-inlet pipe R, in this respect differing from the valves Z, Z', and Z².

50 The operation of the apparatus as thus far described is as follows: As stated in said Clay patent, there is a continuous current or blast of air circulating at all times through the outgoing and return tubes of the main line and of each branch or sub-station line. The operator ascertains to which station he desires to send the carrier, which we will assume to be the branch station, U, shown in the drawings, Fig. 3. He then operates the switch B' by 55 electrical appliances, as set forth in said Clay patent, or by any other suitable apparatus, and then putting the carrier into the receiving-cock Y it is blown through the main-line outgoing tube R until it comes to the switch B'. It is by it deflected from the main line into the branch tube T, the carrier resetting the switch in its passage over the inwardly-

extending end R' thereof, as set forth in said Clay patent, and it is thence blown through the tube T, as shown at T', until it comes to the terminal valve Z. It enters the terminal through the extension of the tube T within it and strikes the end K of the bell-crank lever a sharp blow. This causes the bell-crank to move quickly upward, carrying the gate E 75 with it, as shown in Fig. 1 in dotted lines, the inertia of the bell-crank being taken up by the cushion M without injurious shock. The cushion also acts to instantly throw the lever and the valve back again to their original position, closing the gate-opening; but before this takes place the carrier has passed through the gate into the delivery-spout A', and through it into a suitable receiver placed to catch it, being carried now by its own inertia, 85 because the blast of air is cut off by the reclosing of the gate. The air escapes from the tube T through the slits or opening L therein into the interior of the valve-casing, and from it enters the pipe D². (See Fig. 3.) This pipe 90 D² has a receiving-cock, Y', in it, whereby the carrier may be introduced into the return-pipe V. This return-pipe has no connection with the valve-casing of the station Z, but returns directly to the main-line return-pipe S, 95 which joins at E'. In order, however, that the air may be continued in its circuit throughout the entire pipe system, there must be a valve placed in the branch return-pipe V, to prevent the air from blowing directly 100 through it into the main-line return-pipe, thus cutting out all current in the system which lies beyond the first outgoing and returning branch pipes. Such valve is seen at Z², as before described. Its construction is 105 the same as the valve Z, when, however, it acts as a terminal valve. The carrier is propelled by its inertia through the valve Z² and through the short length of return-pipe (marked V') until it reaches the main-line 110 return-pipe S, where it is caught by the return-current and blown by it back to the home or main station. The air-current proceeds from the valve Z², as before described—that is to say, it passes through the slits L in 115 the side of the inlet-tube V into the casing of the valve, and thence through the pipe Z¹ into the valve Z³, and thence returns to the outgoing main-line tube R and proceeds to and through the remaining station, as before 120 stated, one of which only is shown at Z'. In this station the terminal is shown as in a vertical position, whereas at Z and Z² it is shown in a horizontal position. The main-line valve Z³ is also shown in vertical position. They 125 are so shown in order that the construction and arrangement of the tubing may be more clearly understood, and also because they are used with equal success in either position, and I wish to so illustrate them in my drawings. When horizontally arranged, I prefer to employ a spring, F', to insure the return of the gate to its closed position. The construction and arrangement of the branch 130

pipe D^2 from the terminal Z' to the receiving-cock Y^2 is fully and plainly seen at the right of Fig. 3. These parts may be variously arranged, however, to accomplish the desired result.

I have not yet described the construction and operation of the parts when the operator desires to send the carrier to a point other than to a branch station. It is as follows, 10 assuming that he wishes to send it to the very end of the main line past all the branch stations: As has been already stated, the main line is normally always open, for the reason that no carrier can pass the switch which 15 shunts it off to any branch station without opening the main line again by automatically reopening the switch as it passes through it. This being the case, the operator will not use any of the electrical switch-setting devices when desiring to send a carrier 20 down the main line, but will simply put the carrier into the receiving-cock and start it down the tube R . When it comes to the valve Z^3 , it will open it in exactly the same 25 manner it did the valve of the terminals already fully described, and as soon as it has passed through the valve it will be caught by the blast coming through the pipe Z^4 , which air-blast enters the extension of the tube R 30 through the opening L , and will be carried by it down the main line. In like manner the carrier will open and pass through each of the gates in turn as it meets them, it being 35 of course understood that there is a valve in the main line similar to the valve Z^3 at each place where an outgoing branch tube leaves the main-line tube—in other words, adjacent to each switch and behind it—whereby the air-current may be intercepted and sent 40 through the branch-tube systems.

Each of the valves Z^3 in the branch return-tube is placed as close as may be to the point where the return branch tube joins the main-line return-tube, because the carrier must be 45 propelled from the valve to and into the main-line return-pipe by its own inertia alone.

The necessity of the valves Z^3 in the main line is of course obvious—*i. e.*, that thereby the current or blast of air may be made to 50 traverse to and return from each of the branch stations in turn, returning each time to the main line, along it to the next branch, out and back to and from it, and then along the main line again to the next branch, and 55 so on both in the outgoing and returning circuits.

It will be seen, as before stated, that my new valve is adapted to use as a terminal at a station, as seen at Z and Z' , or as what I 60 will call a "terminal valve in the line," as at Z^2 , or as a regular valve in the main line, as at Z^3 , and all without the slightest change in construction, simply a difference in the location of the hole Q' in the side of the valve-casing, through which the branch pipes D^2 and Z^4 enter, and this change is effected by 65 simply unscrewing the side of the case which

contains this hole, turning it around somewhat and rescrewing it in its new position, so as to bring the hole the other side of the diaphragm C . I so drill the screw-holes that this may be quickly and accurately accomplished. 70

In Figs. 4, 5, and 6 I show somewhat in detail the construction of the gate, the bell-crank lever, the gate-slides, &c. The slides 75 are shown at F , the gate at E , the bell-crank lever at G , the cushion at M , the lugs for the support of the bell-crank lever at I , the pivot on which it turns at H , the connecting bar or bars between the bell-crank lever and the 80 gate at J , and the lugs on the gate at I' .

It will be understood that the gate fits very loosely in its ways and that all its movements are very free. It acts as a cut-off for the air by reason of the pressure of the air 85 against it, which forces it close against its seat in a manner now well understood.

It is obvious that if it be not desired to return the carrier or other thing conveyed from the branch or other like station to the 90 home or sending station, then the receiving-cock Y' and the tube D^2 and the return-tube V , and of course the valve Z^2 , may all be omitted. Then a tube should run direct from the chamber of the valve Z to the valve 95 Z^3 beyond the diaphragm, as shown in dotted lines in Fig. 3. By this means the air-current will be returned to the main-line outgoing-tube R . It is also obvious that the circulation-tube Z^4 could join the main-line outgoing tube just beyond the valve Z^3 , instead of within the chamber therein beyond the diaphragm, because the inertia of the carrier will carry it through the valve and into the extension of the tube R sufficiently far to 105 bring it under the influence of the air-current; but I prefer the method shown, because thereby the connection can easily be made through the already-prepared opening Q' in the side of the valve-casing, and also because the 110 nearer the valve that this connection is made, provided it is not directly on the valve, the better.

I do not limit myself to the details of construction shown and described. It will be 115 manifest to those skilled in the art that many alterations may be made therein and still my invention be employed.

I claim—

1. In a pneumatic-tube system, the combination of an outgoing tube, an automatically-acting valve constructed and arranged to allow the passage of the carrier through and beyond it, a return-tube, a receiving-cock placed in the return-tube, and a connecting-pipe between the automatic valve and the receiving-cock, substantially as set forth. 120

2. In a pneumatic-tube system, the combination of an outgoing main-line tube and a return-tube, an outgoing branch tube, a switch 125 adapted to shunt the carrier from the main-line outgoing tube into the branch tube, an automatically-acting valve in the outgoing branch tube, constructed and arranged to al- 130

low the passage of the carrier through and beyond it, a receiving-cock at the branch station, a pipe connecting the automatic valve at the branch station with the receiving-cock, 5 and a return-tube which joins the main-line return - tube, provided with an automatic valve, substantially as shown, and an automatic valve in the main-line outgoing tube and a delivery-valve at the end thereof, and 10 connecting-tubes between the valve in the branch return-tube and the valve in the main-line outgoing tube and between the valve at the end of the main-line outgoing tube and the receiving-cock in the main-line return-tube, substantially as set forth.

3. The combination, in a pneumatic-tube system, of outgoing and returning main-line tubes and outgoing and returning branch tubes with a switch and automatic valves, 20 substantially as set forth, in the branch return and in the main-line tubes, and a connecting-tube between the valve in the branch return-tube and the main-line tube, whereby the circulation of the air is maintained, and 25 receiving-cocks at the several stations, substantially as set forth.

4. The combination, in a pneumatic-tube system, of outgoing and returning main-line tubes and a branch tube provided with a 30 switch, valves, substantially such as described, in the outgoing main-line tubes near the branch tube and in the outgoing branch tube, and a tube connecting the valve in the branch tube with the main-line outgoing tube beyond 35 the valve therein, substantially as set forth.

5. In a pneumatic-tube system having outgoing and returning main-line tubes and outgoing and returning branch tubes, a valve, substantially as described, interposed in the 40 return branch tube, whereby the current is deflected through a connecting-tube to the main-line tube beyond the junction of the outgoing branch tube with it, and another valve placed in the outgoing main-line tube 45 adjacent to the junction of the branch tube with it, whereby the air is caused to circulate to the branch station before continuing down the main-line tube, substantially as set forth.

50 6. The combination, in a pneumatic-tube system, of outgoing and returning main-line tubes, outgoing and returning branch tubes, a switch placed at the junction of the outgoing branch and main tubes, constructed 55 and arranged to be automatically shifted by the passage of the carrier over it, and automatic valves, substantially such as shown, in the main and branch tubes, whereby the circulation of the air is maintained, substantially as set forth.

60 7. A valve for pneumatic - tube systems,

comprising a case having an opening in one side and divided crosswise by an apertured diaphragm, a gate adapted to cover the aperture in the diaphragm, inwardly-extending 65 tube ends coincident with the aperture in the diaphragm and provided with necessary openings for the passage of the air, and a lever attached to the gate, one end whereof lies in the path of the carrier, whereby the carrier will 70 automatically open the gate, substantially as set forth.

8. A valve for pneumatic - tube systems, comprising a case having an opening in one side and divided crosswise by an apertured 75 diaphragm, a gate adapted to cover the aperture in the diaphragm, inwardly-extending tube ends coincident with the aperture in the diaphragm and provided with necessary openings for the passage of the air, and a lever attached to the gate, one end whereof lies in the path of the carrier, and a retractile spring 80 for the gate, whereby the gate will be automatically opened and closed upon the passage of the carrier, substantially as set forth. 85

9. A valve for pneumatic - tube systems, comprising a case having one side removable and provided with an opening, the case being divided crosswise by an apertured diaphragm, a gate adapted to cover the aperture in the 90 diaphragm, inwardly-extending tube ends coincident with the aperture in the diaphragm and provided with necessary openings for the passage of the air, and a lever attached to the gate, one end whereof lies in the path of the 95 carrier, substantially as set forth.

10. A gate constructed and arranged to be used in the closing of openings in pneumatic tubes, consisting of a piece of sheet metal having a depression made therein within the 100 area of the hole which the gate closes, and lugs riveted to the reverse side of the gate from the gate-seat, the rivet-head lying within the depression, substantially as set forth.

11. A valve for pneumatic - tube systems, 105 comprising a case divided crosswise by an apertured diaphragm, a gate adapted to cover the aperture in the diaphragm, inwardly-extending tube ends coincident with the aperture in the diaphragm and provided with necessary 110 openings for the passage of the air, and a lever attached to the gate, one end whereof lies in the path of the carrier, substantially as set forth.

Signed at New York, in the county of New 115 York and State of New York, this 20th day of November, A. D. 1888.
